UNITED STATES PATENT OFFICE.

GEORGE EDWARD BELCHER, OF STOUGHTON, MASSACHUSETTS.

LAST.

1,134,502.

Specification of Letters Patent.

Patented Apr. 6, 1915.

Application filed June 23, 1913. Serial No. 775,266.

To all whom it may concern:

Be it known that I, GEORGE E. BELCHER, a citizen of the United States, residing at Stoughton, county of Norfolk, Commonwealth of Massachusetts, have invented certain new and useful Improvements in Lasts, of which the following is a specification.

This invention relates to lasts and particularly to a divided or collapsible last for shoes. In this type it is especially desired that the last be rigid and firm when in expanded position so as to avoid any possibility of its collapse during the subsequent shoe operations, while being capable of intentional collapse to a sufficient degree to permit the shortening of the last sections so as to allow the last to be removed from the shoe.

To the end therefore of providing a simple last structure and one capable of economical production with a maximum rigidity and strength, I have devised my present invention. In it I use a novel form of link or hinge connection for the fore and heel sections which has been shown to be highly efficient and practical for the purposes intended.

The construction and operation of my last will be more fully set forth in the specification that follows and as illustrative of my invention, I have shown in the drawings, several embodiments of my device which have been found well adapted to practical use.

Throughout specification and drawings, like reference numerals are employed to indicate corresponding parts, and in these drawings: Figure 1 is a central longitudinal section through a last in accordance with my invention and indicating in dotted lines a partial showing of the heel section position when the last is collapsed, lack of space preventing a full showing of the collapsed position of the heel part. Figs. 2 and 3 are views of the rear and front faces of the fore and heel sections respectively. Fig. 4 is a transverse section on the line 4-4 of Fig. 1 looking in the direction of the arrows. Fig. 5 is a partial section of a modified embodiment in which I use a locking latch to hold the last sections in expanded position. Fig. 6 is a partial section of another modification. Fig. 7 is a view at right angles thereto, and Fig. 8 is a partial section of still another modification.

The embodiments illustrated in the draw-

ings comprise a heel part 1 and a fore part 2 separated by cuts which give to the parts a shouldered bearing. This leaves in the rear of the heel part a projecting angle 60 formed by the surface 4 which is inclined slightly forward and an intersecting surface 5 which is sawed on a curve starting from the point of intersection and running back toward the rear of the heel section and terminating at a point directly below said point of intersection and at the bottom of the last.

The fore part has a face 6 corresponding to the curved face 5 of the heel part and bearing closely against said face when the sections are in normal position. This face 6 however, is extended upwardly beyond the point of intersection of the faces 4 and 5 and intersects a slightly rearwardly inclined face 7 at a point substantially in line 75 with the upper edge of the face 4. The face of the heel part and that part of the face 6 included between the respective points of intersection of the faces 4 and 5 and the faces 6 and 7 define a substantially V-shaped 80 space which permits the faces 4 and 7 to contact when the face 5 rides up along the face 6, as partially shown in dotted lines Fig. 1. The face 7 is therefore a stop face 85 to limit the upward movement of the heel part.

The heel part has a bore tapped through it near its bottom starting from the face 4 and running back as far as the jack hole 10 and the fore part has a somewhat sector-shaped recess extending from its rear face 6 well up toward the toe. The hinge or link connection which permits the heel part to be moved relative to the fore part is rigid in the bore of the heel part and pivoted in the recess of the fore part so as to have an up and down play therein. This connection is formed as a link having a cylindrical body portion 8 pinned in the heel part just forward of the jack hole 10 by a transverse pin 100 11. Near the curved face 5 of the heel part the body portion 8 has a fin 9 projecting therefrom to prevent its turning laterally and said body portion is also shouldered at 12 to provide a narrow shank 13, preferably 105 rectangular in cross section as shown. This shank near its forward end is pivoted in the fore part by a transverse pin 14 and fits and is guided in a channeled guide member seated in and substantially conforming to 110 the sector shaped recess of the fore part. Said guide member comprises a bottom strip

15 and integral side walls 16 which define a substantially U-shaped recess 17. The guide member is pinned within the fore part at its forward end by the pin 14 of the shank 5 which passes transversely through the side walls 16. Adjacent to the pin 14 the walls 16 are extended upwardly in the form of substantially sector shaped wing pieces 18. The rear faces of these wings are curved to 10 conform to the curvature of the rear face 6 of the fore part and have as their approximate center the pin 14 which pin also represents the approximate center for the curve on which the face 6 is sawed. These curved 15 faces of the wings project slightly beyond the face 6 as tongues 19 and are adapted to fit within registering grooves 20 in the curved face 5 of the heel part. These grooves 20 extend from end to end of the 20 face 5 and therefore provide a double tongue and groove connection for the heel and fore parts. The narrow forwardly projecting tongue of wood 21 left between these grooves enters within the channel 17 formed by the 25 bottom strip 15 and side walls 16 of the guide member to frictionally engage the inner faces of the tongues 19 of the wing pieces. The shoulders 12 of the shank limit the downward movement of the heel part by 30 striking against the wood of the heel part left when the bore is tapped therethrough.

The operation of this type of last is substantially as follows: The last is normally in the position shown in Fig. 1 in which 35 position the bearing faces 5 and 6 lie in contact with each other after the manner of a knuckle and socket joint. When it is desired to collapse the last the heel part is thrust upwardly causing the face 5 to ride 40 up along the face 6 in an arcual path. In this movement the heel part is guided along the fore part by the tongue and groove connections 19 and 20 and 17 and 21 until the forwardly inclined face 4 of the heel part 45 abuts against the rearwardly inclined stop face 7 of the fore part. While the heel part is describing this movement relative to the fore part the shank 13 is being swung upwardly on its pivot in the fore part and 50 works in the space 17 between the lateral wings 18 reaching the limit of its movement when the faces 4 and 7 of the last parts contact.

The frictional engagement of the tongue 55 and groove connections hereinbefore described is sufficient under ordinary conditions of use to hold the last parts in lasting position, but under certain conditions it is desirable to have a positive lock to resist the 60 breaking strain. To meet such conditions I provide the positive locking device shown in Fig. 5. In this embodiment the link 13 is cleared at one side as indicated at 22 to expose one end of a pivot pin 23 and provide 65 working space for a latching device. This

latch is in the form of a link 24 which is pivotally mounted on the pin 23 and is provided near its upper end with a locking notch 25 adapted for engagement over a second pin 26 fastened in the wood of the fore 70 part. The free end of this latch projects up into the V-shaped space between the faces 4 and 7 so as to be easily accessible to the operative.

In Figs. 6 and 7 I have illustrated as an- 75 other embodiment a form of connection especially designed to give an increased bearing to the shank to successfully resist the breaking down strain of the sole leveler. The nose 27 of the shank is in this embodiment 80 slightly tipped up in the manner of a hook to engage over a transverse pin 28 in the wood of the fore part. This engagement not only affords an increased bearing but also serves to limit the downward movement of 85 the shank as will be understood.

In Fig. 8 I have illustrated a modified 90 manner of securing the guide member in the fore part by a second pin 29 which is independent of the shank 13.

These and various other modifications coming within the spirit of my invention may obviously be resorted to within the limits of the appended claims.

What I therefore claim and desire to se- 95 cure by Letters Patent is:

1. A last of the class described comprising a fore part and a heel part having suitable bearing therebetween, a guiding member in one of said parts having a slot vertically 10 disposed therein, and a link pivoted at one end in said part and located within the slot of said guide and having its other end fixed in said other part, the edges of said guide extending beyond the bearing surface of said 10 first named part, the bearing surface of said second named part being grooved to receive said projecting edges to guide the same.

2. A last of the class described comprising a fore part and a heel part having co-operating bearing faces, one of said parts having a grooved face, a channeled guiding member in the other part having its edges exposed to engage said grooves, and a connection pivoted at one end in said part and guided within the channel of said guide and having its other end fixed in said other part.

3. A last of the class described comprising a fore part and a heel part having suitable bearing surfaces therebetween, the bearing 120 surface of one of said parts being grooved, a guide member located in the other of said parts and having its edges exposed to have continuous engagement in said grooves throughout the movement of the parts, a 121 link pivoted in said guide at one end and fixed in the co-operating last part at its other end, and shoulders on said link engaging the exposed edges of the guide member.

4. A last of the class described comprising 120

a fore part and a heel part having suitable bearing surfaces therebetween, a guiding member in one of said parts and having a slot vertically disposed therein, and a link 5 pivoted in said guiding member and fitting within the slot thereof, said guiding member having its edges exposed and curved concentric with the pivot of said link, said link having shoulders slidably engaging the ex-

posed edges of said guiding member and arranged to find continuous bearing thereon.

In testimony whereof I affix my signature in presence of two witnesses.

GEORGE EDWARD BELCHER.
